DESIGN FOR A TEXTILE FABRIC

Philip R. Costigan, Kew Gardens, N. Y., assignor to Joseph B. Hoffman, New York, N. Y.

Application July 24, 1936, Serial No. 64,022

Term of patent 3½ years

To all whom it may concern:

Be it known that I, Philip R. Costigan, a citizen of the United States, residing at Kew Gardens, in the county of Queens and State of New York, have invented a new, original, and ornamental Design for a Textile Fabric, of which the following is a specification, reference being had to the accompanying drawing, forming part hereof.

The figure is a plan view of the fabric showing my new design.

I claim:

The ornamental design for a textile fabric, as shown.

PHILIP R. COSTIGAN.
